E. E. TROWBRIDGE.
PAVEMENT AND BRICK FOR USE THEREIN.
APPLICATION FILED FEB. 12, 1916.

1,259,933.

Patented Mar. 19, 1918.

UNITED STATES PATENT OFFICE.

EMORY E. TROWBRIDGE, OF KANSAS CITY, MISSOURI.

PAVEMENT AND BRICK FOR USE THEREIN.

1,259,933.

Specification of Letters Patent. Patented Mar. 19, 1918.

Application filed February 12, 1916. Serial No. 77,933.

To all whom it may concern:

Be it known that I, EMORY E. TROWBRIDGE, a citizen of the United States, residing in the city of Kansas City, county of Jackson, 5 and State of Missouri, have invented certain new and useful Improvements in Pavements and Bricks for Use Therein, of which the following is a specification.

This invention relates to improvements in 10 pavements and bricks for use therein and more particularly to the vertical fiber brick. In bricks of this character it is advantageous that the vertical face of the brick be provided with grouting spaces to receive 15 a binder such as an asphalt filler or the like.

Among the salient objects of the invention are to provide a brick equipped with the desired or requisite number of grouting 20 spaces on its vertical faces, which grouting spaces are so arranged as to obtain a maximum binding surface for the filler or grout and which grooves are so arranged that the sections of asphalt filler or the like when 25 the bricks will be laid in a pavement will be uniformly spaced; to provide a brick in which these grooves are so disposed on the vertical faces of the brick and if desired on the vertical ends whereby the grouting 30 spaces will be in proper position when the bricks are laid in a pavement regardless of the way in which the bricks are laid, the same result will be obtained regardless which horizontal face of the brick is upper- 35 most and regardless of the fact that the brick may be turned end for end. The above arrangement very materially facilitates the laying of the bricks in pavements for the reason that no attention need be paid 40 to which horizontal face of the brick is uppermost or which vertical face of the brick lies against the previously laid layer or row. Furthermore, the construction of the brick itself is such that in burning the 45 bricks in a kiln many more horizontally extending heat passages are provided. The process of making these bricks is in general described in my issued Patent No. 1,154,741, of September 28, 1915, although the present 50 brick is so constructed that when the green bricks are piled in the kiln they will be more effectively burned, in fact, the method of burning these bricks is an improvement over that set forth in said patent and will 55 be apparent to those skilled in the art. It will thus be seen that the present invention

not only provides a brick which can be more effectively burned in the kiln but very materially facilitates the laying of the pavement and further provides an increased 60 number of grouting spaces for the binder or filler. By reference to the drawing hereinafter referred to and more particularly to Fig. 2 and comparing the same with Fig. 3 of the aforesaid issued patent it will be 65 seen that the increased passages for the gases of combustion are readily obtained. Preferably the vertical grooves are roughened as shown in the drawing in order that the binder will more effectively unite with the 70 brick itself. As a still further object of the invention the grooves are so arranged that when the bricks of adjacent rows are staggered as is required in the laying of pavements the grooves on the opposite meeting 75 vertical faces will be staggered or alternately arranged as shown clearly in Fig. 2. As a subsidiary object of the invention the ends of the vertical faces of the bricks are provided with what may be called half 80 grooves which coöperate with the corresponding half groove of adjacent bricks. This is also clearly shown in Fig. 2 of the drawings.

I am, of course, aware that heretofore 85 vertical fiber bricks have been made with grooves and sometimes with grooves and projecting ribs but I am not aware that any brick has been made embodying the advantages of the present invention or that 90 any pavement has been laid in a manner hereinafter described and shown in the drawings.

In the drawing:

Figure 1 is a perspective view of my im- 95 proved brick.

Fig. 2 is a similar view showing the manner of forming the pavement with such bricks.

Referring to the drawing, 1 designates as 100 a whole the brick having vertical fibers 2, 2 and being substantially rectangular in shape as shown in the drawing. Each vertical face 3 of the brick is provided with two centrally disposed and equi-spaced grooves 105 4 which serve as grouting spaces and end semi-grooves 5. It is to be noted that the grooves 4 on each vertical face are not only spaced equi-distant from each other and equi-distant from the ends of the brick but 110 that they are directly opposite the corresponding grooves on the opposed vertical

faces. Preferably the vertical ends of the brick are provided with vertical grooves 6 as shown. These grooves are spaced midway between the vertical faces of the brick.

5 As is well known uniformity of burning of brick throughout its entirety is highly desirable and this is accomplished better by providing when the green bricks are burned in the kiln as many passages for the 10 gases of combustion as possible. The process of this manufacture as heretofore stated has been described in my prior patent and the feature of providing grooves on both 15 faces of the brick increase the uniformity of burning as is apparent. The result will be that we will get as nearly perfect a brick as is possible in so far as uniformity of burning is concerned.

In addition, however, this brick is not 20 only better in itself in so far as its quality is concerned but makes a better pavement in that the bricks can be more effectively bound together and furthermore can be much more economically laid. In Fig. 2 I have shown 25 portions of three rows of a pavement A, B and C respectively. It will be noted that the bricks of row B are staggered with reference to the other two rows so as to break joints transversely of the pavement 30 itself. This is required in the laying of pavement. Now it will also be noted that the grooves or grouting spaces 4 on the inner face of row A are alternately disposed relative to the grouting spaces 4 of row B, 35 the result being that a maximum surface of the vertical faces of the bricks come in contact with the filler or binder. This, of course, is highly desirable. It will also be noted that the semi-grooves 5 of the adjacent 40 ends of the bricks in each row will form a single grouting space. Furthermore, the grooves 6 on the vertical ends of the brick register to form the grouting spaces as clearly seen in Fig. 2. Now it will be ap-

parent that the foregoing arrangement of 45 the pavement takes place regardless of which horizontal face of the brick is uppermost and the same arrangement is true if any of the bricks be turned end for end. As is well known these bricks are laid very 50 rapidly, frequently from a jumbled pile of bricks in forming the pavement. The cost of laying the pavement is very materially reduced if the bricks can be laid without the necessity of having to arrange the proper 55 face of the brick in the proper position, as for example, would be the case were the brick shown in my issued patent used. This is of such importance as to permit a contractor bidding for a particular job to make 60 a much lower bid and thus secure the award. In addition the pavement itself when completed is as heretofore stated a better pavement than that formed by any of the bricks 65 of the prior art.

The invention is not limited to the details of construction shown except as set forth in the appended claim.

I claim as my invention:

A pavement comprising a plurality of 70 rows of elongated bricks, each having extending from top to bottom on its elongated vertical faces a plurality of relatively wide and shallow vertical grooves of less width than the wall faces between the grooves, the 75 bricks of adjacent rows being laid with the grooves in the face of one row of bricks centrally disposed of and opposite to the wall faces between the grooves of the adjacent row of bricks, and with portions of said 80 faces on each side of each groove of one row of bricks in contact with corresponding portions of the faces of the adjacent row and cementitious material filling said grooves and cementing the juxtaposed faces of the 85 bricks together at a plurality of isolated points relative to the face of each brick.

EMORY E. TROWBRIDGE.
